UNITED STATES PATENT OFFICE.

GEORGE L. WILCOX, OF ESCALON, CALIFORNIA.

EARTH SCRAPER.

Application filed February 18, 1921. Serial No. 446,104.

To all whom it may concern:

Be it known that GEORGE L. WILCOX, citizen of the United States, residing at Escalon, in the county of San Joaquin and 5 State of California, has invented certain new and useful Improvements in Earth Scrapers, of which the following is a specification.

My invention relates to improvements in 10 earth scrapers wherein earth is to be removed and deposited elsewhere in a prescribed manner.

The object of my invention is; first, to provide a scraper that can be used with and 15 operated from the tractor seat by the driver thereof in leveling land and making levels for irrigation; second, to afford a means of releasing the entire load at once or of spreading same over the surface of the 20 ground, at the will of the operator; third, to provide an adjustable cutting blade; fourth, to reduce to a minimum the exertion necessary on the part of the operator, by providing an end-gate separate from the 25 main frame and side walls, counter-balanced on a rocker frame; fifth, to provide means for holding the end-gate in place by two arms and catches and providing a device for their simultaneous release; sixth, 30 to provide a single counter-balance so placed as to perform two separate functions.

I attain these objects by the mechanism illustrated in the accompanying drawings, in which—

35 Figure 1 is a side elevation of the device, with the nearest wheel and side wall of the scraper removed.

Fig. 2 is a top plan view thereof.

Fig. 3 is a fragmentary view of a catch 40 member and its actuating means.

Fig. 4 is a front fragmentary view of the catch-actuating and dumping lever mechanism.

Fig. 5 is a cross section taken on the line 45 5—5 of Fig. 4.

Referring now more particularly to the characters of reference on the drawings, I provide a frame consisting of longitudinal 50 rails, 1, a transverse cross beam 2, raised somewhat above the plane of said rails, and a forward portion 3, the latter being an extension of the side rails 1 but closer together. This frame is carried on rear wheels 4 and a forward caster wheel 5.

55 Supported on convexly curved pads 2^a on the beam 2 is a rocker frame 6, held against

lateral and longitudinal movement thereon, but permitted fore and aft tilting by reason of pins 6^a fixed in the blocks 2^a and projecting up through tapered slots 6^b in the frame 6, as shown in Fig. 1.

Hinged to the rear end of the rocker frame 6 is an end gate 7, this frame and end gate being raised and lowered for spreading and loading by suitable means, such as 65 through the medium of a link 8 pivoted to the front end of the rocker frame and connected to a lever 9 pivoted on the frame portion 3 and provided with a usual form of 70 pawl and quadrant structure 9^a.

Arms 10 extend from adjacent the lower end and sides of the gate 7 upwardly and forwardly of the same. They are flexibly connected to said gate, and to the scraping blade 12 below said gate, by means of adjustable brackets 11, which converge to common pivotal connections with said arms. 75

The end gate is concave in form and so constructed and hinged that practically its entire weight is to the rear of a vertical line 80 through its hinge pivot. It is reinforced with angle irons 13, which serve as the hinges and which extend down to an additional reinforcement flange 14, which extends across the lower end of the end gate. 85

The blade 12 is provided along its upper edge with a similar flange 15 and is flexibly connected to the end gate for angular adjustment relative thereto by means of loosely placed bolts 16, these bolts being located near the inner edges of the flanges and passing therethrough. Angular adjustment of the blade with respect to the end gate is effected by means of adjustable bolts 17 screwed into and through the flanges 14 95 and which bear against the flanges 15.

The length of the corresponding brackets 11 may be adjusted to suit by reason of the adjusting nuts 11^a thereon on both sides of the blade 12. 100

Further adjustment of the end gate and blade, to meet extreme conditions, may be had by changing the point of connection of the brackets 11 with the arms 10 to any one of several holes 10^a in the latter. 105

Fixed to and projecting upwardly and normally to the rear from the end gate 7 is an arm 18, connected by a rod 19 to a similarly disposed arm 20 fixed on a shaft 21, journaled on the forward end of the rocker frame 6.

Fixed onto the shaft 21 and projecting

above and normally to the rear of the same are counterweights 22.

Pivoted to the arm 20 and extending forward thereof is a link bar 23, pivoted at its forward end to an arm 24 which is journaled to the frame 3 below this point, on a shaft 24^a. The upper end of this arm is pivoted to a lever 25, which extends above this point to provide a hand-hold, and is free at its lower end.

Formed with the lever 25 and embracing the arm 24 between the connections of the latter with the lever 25 and the link 23 is a slotted yoke 26, the width of the slot being such as to easily receive the arm 24 therethrough, while its length is such as to permit a certain amount of relative movement between said arm and lever in the direction of their throw.

Pivoted onto the lower end of the lever 25 is a rearwardly extending shifting rod 27 having longitudinally disposed and spaced pawls 27^a either one of which at a time is adapted to engage a lug 28 projecting upwardly from a shaft 29 transversely journaled on the frame members 3, the outer ends of this shaft having inverted V shaped catch portions 30 formed therewith, adapted to seat in notches 31 cut in the under face of the arms 10 when the end gate is closed, or in similarly formed but oppositely disposed notches 32 in said arms when the end gate is opened up to the rear and the arms 10 moved likewise.

These notches and catch portions are formed and arranged with respect to each other and to the axis of turning of the shaft 29 so that when any pulling or pushing pressure is on the shaft, there will be no tendency for the shaft to rotate automatically so as to cause undesired release of the catches from the notches.

Side walls 33 are provided for the scraper, these being fixed onto the side rails 1, and extending to the rear of the normal plane of the end gate, being provided with rearwardly disposed guides 34 so as to insure the entrance of the end gate into proper place when closing.

The operation of the device is as follows:—

For scraping and spreading, the end gate and blade members are set as shown in Fig. 1, the notches 31 on the arms or bars 10 then being engaged by the catches 30. Spreading, as hereinbefore stated, is effected by movement of the lever 9, which as will be seen, causes the rocker frame to tilt, raising the end gate in a substantially vertical plane, the arms 10 moving about the catches 30 as an axis and serving to prevent the end gate from opening up to the rear as long as the catches are engaged.

Dumping action of the scraper may be had irrespective of the position of the lever

9 and rocker frame by the following operation, the purpose of which is to quickly and easily raise or open the end gate to the rear, so that the load will be discharged in a compact mass.

Presuming that the parts are positioned as shown in the drawings, the lever 25 is pulled toward the front end of the scraper. The first result of this movement is to cause said lever to turn about the connection of the arm 24 therewith as an axis, while the member 27 at the lower end of the lever moves to the rear, rotating the shaft 29 and reversing the position of the catches 30 so that the arm-notches 31 are readily and automatically disengaged therefrom when any rearward pull comes on the arms 10, such as is of course present when the forward movement of the lever 25 is continued.

By the time this is done, the forward end of the slotted member 26 will have engaged the adjacent edge of the arm 24. With any further pulling movement on the lever 25 therefore the lever and arm, and the member 27, moves forward as the unit causes the arm 18 to be moved and thus opening the end gate. At the same time the freed arms 10 move to the rear until the notches 32 are engaged by the catches 30, these having been already moved in position to be received by said notches, the cut of which, as will be seen, is reversed from that of the notches 31 for this purpose. Now when the shaft 29 was rotated in a counter clockwise direction, the position of the lug 28 was of course reversed, and is now in position to be engaged by the rearmost lug 27^a on the member 27, and the shaft 29 rotated in the opposite direction to restore it to normal position when the movement of the lever is reversed to return and close the end gate after dumping.

Now with the forward movement of the arm 18, the counterweights likewise moved forward, and their functioning or action is reversed from that normally had. When the parts are in spreading or loading position, as shown in Fig. 1, these weights are set above and to the rear of their pivots, thus exerting a rearward push on the link 19, which tends to hold the end gate from opening to the rear, and also takes some of the strain off the arm 10.

In addition to this function however, the main action of these counterweights when in the above named position is to act as a positive counterbalance to the dead weight of the end-gate and blade by reason of the position of these counterweights ahead of the pivotal point of the rocker frame.

Now as the arm 18 moves forward, the position of the counterweights with respect to their pivots is reversed, and as soon as their center of gravity passes forward of a vertical line through their pivots, they exert

a pull on the link 19, tending to open the end gate, the pulling pressure increasing the further forward these weights are swung.

At the same time, as the end gate is raised, its overhanging weights with respect to its pivotal connection is increased in proportion to the amount it is turned on its hinges. This increase in overhang weight is compensated for and equalized by the similarly increasing counterweighting effect of the members 22, whose weight bears a direct relation to that of the end gate, so that a very smooth and easy dumping action is had.

15 I am aware that earth scrapers, having a main frame carried on wheels, capable of being operated from a tractor seat are now in use. I therefore do not claim such combination broadly but

20 I claim;

1. In an earth scraper, an end gate hinged along its upper edge and mechanical means mounted in connection with the gate and acting thereon for raising or lowering the same in a substantially vertical plane and for independently opening said end gate to the rear.

2. In an earth scraper, an end gate normally vertical and hinged at its upper edge and adapted to move upwardly to the rear about its hinged connection as an axis, and counterweight means operatively connected with the end gate and so arranged as to maintain a constant ratio of effectiveness 35 with respect to the end gate as the latter is raised to the rear and to exert a reversed action as the end gate approaches its closed position.

3. In an earth scraper, an end gate, a separate cutting blade below the same, transverse and substantially parallel plates attached along the adjacent edges of the end gate and blade, bolts passing freely through said plates, the heads thereof bearing 45 against the opposed faces of the plates, and adjusting bolts screwed through one of said plates and bearing against the other.

4. In an earth scraper, a main frame, a rocker frame mounted thereon, an end gate hinged to said rocker frame, means for tilting said rocker frame whereby the end gate will be raised vertically, and independent means for swinging the end gate upwardly to the rear about its hinged connection as an 55 axis.

5. In an earth scraper, a hinged end gate adapted to be opened upwardly to the rear, locking means for holding the end gate in its open or closed positions, and commonly 60 actuated means for first releasing the locking means and subsequently moving the end gate to open or close the same.

6. In an earth scraper, a hinged end gate adapted to be opened upwardly to the rear, locking means for holding the end gate in 65

its open or closed positions, means for releasing the locking means and for then moving the end gate to an open or closed position, and means whereby locking of the end gate in either of such positions will then be automatically effected. 70

7. In an earth scraper, a hinged end gate adapted to be moved to assume different positions, arms flexibly connected to said gate, and having notches provided on the under 75 side thereof, catch members adapted to automatically engage either set at a time of the notches, and lever means for releasing said catches and for then moving the end gate to a new position. 80

8. In an earth scraper, a hinged end gate adapted to be moved to assume different positions, arms flexibly connected to said gate, and having notches provided on the under 85 side thereof, catch members adapted to automatically engage either set at a time of the notches, lever means for releasing said catches, lever means for moving the end gate, and connecting means between said lever means whereby after the catch lever 90 means is actuated the gate-moving lever means will be brought into action.

9. In an earth scraper, a hinged end gate adapted to be moved to assume different 95 positions, arms flexibly connected to said gate, and having notches provided on the under side thereof, catch members adapted to automatically engage either set at a time of the notches, lever means for releasing said catches, lever means for moving the end gate 100 connected to the first named lever means, and means whereby with a continuous movement of said first named lever means the latches are first disengaged and the end gate then moved. 105

10. In an earth scraper, an end gate hinged at its upper edge and normally hung vertically but adapted to be swung upwardly to the rear, and counterweight means operatively connected to the end gate acting to balance the weight of the end gate when the latter is in the vertical position; and to exert a counterbalancing effect in direct ratio to the increasing resistance of the end gate as the latter is opened to the rear. 110

11. In an earth scraper, a frame, an end gate hinged at its upper edge thereto and normally hung vertically but adapted to be swung upwardly to the rear, counterweight means pivoted transversely on the frame and tilting to the rear of a vertical plane when the end gate is in its vertical position, connecting members between the counterweight means and the end gate whereby the effect of the former is transmitted to the latter, and lever means connected to the connecting members and arranged to pull the latter forward to open the end gate, whereby the counterweight is tilted forward of a vertical plane. 115 120 125 130

12. In an earth scraper, a hinged end gate adapted to be moved to assume different positions, arms flexibly connected to said gate, and having notches provided on the under side thereof, catch members adapted to automatically engage either at a time of the notches, a transverse turnable shaft on which said catches are mounted, lever means for turning said shaft sufficiently to disengage the catches, separate lever means operatively connected to the end gate to move the same, and means between the two said lever means whereby after the former has been moved to release the catches the other lever means will then be actuated to move the end gate with a continuation of the movement of the catch-releasing lever means.
13. In an earth scraper, a hinged end gate adapted to be moved to assume different positions, arms flexibly connected to said gate, and having notches provided on the under side thereof, catch members adapted to automatically engage either set at a time of the notches, a transverse turnable shaft on which said catches are mounted, lever means for turning said shaft sufficiently to disengage the catches, separate lever means operatively connected to the end gate to move the same, the upper end of said last named lever means being pivoted to the catch releasing lever, and a slotted member on said catch lever through which the end-gate lever passes, said slot allowing a predetermined relative movement between the levers before either end of the slot engages the edge of the end-gate lever.
14. In an earth scraper, a hinged end gate adapted to be moved to assume different positions, arms flexibly connected to said gate, and having notches provided on the under side thereof, catch members adapted to automatically engage either at a time of the notches, a transverse turnable shaft on which said catches are mounted, a lug projecting radially from the shaft, a double and spaced rigid pawl member disposed to coact with the lug, a lever to which the pawl member is connected, another lever operatively connected to the end gate to move the same pivoted at its upper end to the pawl-lever, and a slotted member on the latter through which the end-gate lever passes.
15. In an earth scraper, a hinged end gate adapted to be moved to assume different positions, arms flexibly connected to said gate and having spaced and opposed notches on its under side, a transverse shaft extending under the arms, and cam-like catch members formed with said shaft and adapted to engage said notches, said catches being so disposed with respect to the shaft that the lever-notches engage the same below the axis of the shaft whereby a rearward pull on the arms will not allow the shaft to turn and disengage the catches.

16. In an earth scraper, a hinged end gate adapted to be moved to assume different positions, arms flexibly connected to said gate and having spaced and opposed notches on its under side, catch members adapted to engage either set at a time of the notches, dual and commonly operated lever means for releasing the catches and then moving the end gate, and means whereby when said lever means is at the end of its travel in either direction the catches will be positioned to automatically engage with the corresponding notches.

17. In an earth scraper, a hinged end gate adapted to be moved to assume different positions, arms flexibly connected to said gate and having spaced and opposed notches on its under side, catch members adapted to engage either set at a time of the notches, dual and commonly operated lever means for releasing the catches and then moving the end gate, and means whereby when said lever means is at the end of its travel in either direction the catches will be positioned to automatically engage with the corresponding notches, while the lever means will then be in a position to immediately disengage the catches when said lever is moved in the return direction.

18. In an earth scraper, an end gate hinged at its upper edge and adapted to be swung upwardly to the rear, and arms flexibly connected to the end gate and adapted to be normally locked in either position of the end gate to prevent movement thereof.

19. In an earth scraper, an end gate hinged at its upper edge and adapted to be swung upwardly to the rear, means for moving the end gate, and locking means for the end gate arranged to automatically lock and prevent the same from further movement after being moved to an open or closed position.

20. In an earth scraper, an end gate hinged at its upper edge and adapted to be swung upwardly to the rear, lever means for moving the end gate, locking means for the end gate to hold it in certain positions, and means between the lever and lock means whereby the latter will be released before any movement of the end gate can be had.

21. In an earth scraper, a main frame, a rocker frame, an end gate pivoted to the latter, means for tilting the rocker frame, arms flexibly connected to the end gate, and catch members on the main frame releasable at will to allow the end gate to swing about its hinge connection and arranged to allow vertical swinging movement of the arms as the rocker frame is tilted and the end gate raised vertically.

In testimony whereof I affix my signature.

GEORGE L. WILCOX.
